BOTTLE CARRIER

Robert P. Smith, Crawfordsville, Ind., assignor to
The Hoosier Crown Corporation, Crawfords-
ville, Ind.

Application March 14, 1940, Serial No. 323,968

1 Claim. (Cl. 224—45)

The present invention relates to bottle carriers of a type adapted to accommodate bottles of soft drinks and similar beverages and has for its primary object to provide a basket type carrier embodying a pair of pivoted side portions constructed of wire and adapted for engaging the outer sides of a double row of bottles placed within the carrier and providing handle means having slideable engagement with said side members to clamp the latter into engagement with the bottles, the weight of the bottles assisting in increasing the clamping action of said handle.

A further object is to provide a device of this character of simple and practical construction, which is strong and durable, relatively inexpensive to manufacture and otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view,

Figure 2 is a top plan view,

Figure 3 is an end elevational view, and

Figure 4 is a fragmentary end elevational view showing the bottle clamping members in open position.

Referring now to the drawings in detail, the numeral 5 designates a bottle supporting member which is constructed of a relatively narrow strip of metal having upstanding end portions 6 to provide a bottom member of substantially U-form.

Each of the upstanding ends 6 are provided with a pair of openings 7 adapted to receive the end portions 8 of a pair of wire bottle clamping members designated generally at 9.

The ends portions 8 are shaped substantially in the form of hooks, as shown more clearly in Figure 1 of the drawings, the portion of the wire extending from said hooks rising substantially vertically to form end portions 10 which merge with outwardly extending horizontal portions 11 which curve in a longitudinal direction with respect to the bottom 5 and are provided at spaced intervals with inwardly bent spacing members 12. The portion of the wire between said spacing members 12 is curved outwardly to provide bottle accommodating recesses 13 for conformably receiving the side walls of the bottles 14 when positioned upright on the base 5.

A pair of the clamping members 9 are arranged at opposite sides of the base 5 whereby to co-

operate in clamping a double row of the bottles in position when supported on the base.

5 A substantially U-shaped handle member 15 is provided which has its end portions formed into loops 16 positioned horizontally and constituting slides which are slidably mounted on the vertical end portions 10 of the clamping members.

10 At the junction between the vertical end portions 10 and the horizontal portions 11 of the clamping member is formed a notch 17 within which the slide 16 is seated, when the latter is moved in its uppermost position, to restrain downward gravitating movement of the slide and 15 the handle and thus to maintain the clamping members in their clamping engagement with the bottles.

10 From the foregoing it is apparent that by a 20 downward movement of the handle 15 that the clamping members will be released to permit outward pivotal movement thereof whereby to release the bottles 14 and upon an upward movement of the handle relative to the base 5 the slide 16 will serve to draw the clamping members inwardly into clamping engagement with the bottles. The weight of the bottles thus serves to 25 assist in maintaining the device in bottle clamping position.

It is believed the details of construction, advantages and manner of use of the device will be 30 readily understood from the foregoing without further detailed explanation.

Having thus described the invention, what I claim is:

35 In a carrier for bottles, an elongated rigid member providing a rest for bottles positioned vertically thereon and having upturned ends, jaw members coactive with each other in surrounding and gripping the bottles above the rest 40 and including horizontal portions normally elevated in bottle holding position and vertical portions, said vertical portions having the free ends thereof hinged on the upturned ends of the elongated rigid member whereby the horizontal portions can move out of elevated position and away from each other whereby bottles may be placed on and removed from the rest, said horizontal portions having curved offsets to conform 45 to the walls of the bottles and to act as spacers 50 between the bottles, and a bail having elongated looped portions at the ends thereof slidably receiving the vertical portions of the jaw members to sustain the latter in bottle holding position whenever the bail is under the load of the 55 bottles.

ROBERT P. SMITH.
